The ornamental design for an adaptor for holding a tap threading device, as shown and described.

DESCRIPTION

FIG. 1 is a perspective view of an adaptor for holding a tap threading device showing my new design;

FIG. 2 is a top plan view thereof, wherein the bottom plan view is a mirror image; both opposing views are taken in the direction of arrows 2 in FIG. 6;

FIG. 3 is a side elevational view thereof, wherein the opposing side elevational view is a mirror image; both opposing side views are taken in the direction of arrows 3 in FIG. 6; FIG. 4 is a front elevational view thereof taken in the direction of arrow 4 in FIG. 6; and,

FIG. 5 is a rear elevational view thereof taken in the direction of arrow 5 in FIG. 6; and,

FIG. 6 is a perspective view thereof, wherein reference legends are provided to coordinate with the plan and elevation views shown in FIGS. 2-4.

The broken lines in the drawing illustrate environmental structure and portions of the adaptor for holding a tap threading device that forms no part of the claimed design.
